The Schedule referred to in the Letters Patent and making part of the same containing a description in the words of the said Edmund Warren himself of his improvement in the . . . Threshing Machine for Corn & all kinds of grain and Seed.

This Machine is constructed by a frame of Wood or iron, of a size to suit the power to be applied. but a size suitable to be drawn by one Horse, is two feet wide, and about two feet eight inches long, and maybe from two feet six inches, to two feet eight, inches high. A cylinder of common wood about twenty four inches long, with spikes of iron about one inch long, and five eighths of an inch in diameter or square & in rows, about four inches apart. the spikes of one row coming in range of the Spur of the next, and so on interchangeably round the surface of the cylinder. The size of which should be proportioned to the last to be given. A tooth or each cylinder should be so ground as to give sixteen hundred revolutions in a minute. A concave is formed by round bars of iron about five eighths of an inch diameter, or square bars about the same size twisted forming a spiral surface. These are stationed so as not to turn and are about eight in number, and one fourth of an inch from each other beginning within three inches of the top of the machine on which the cylinder is stationed, and passing under a little past the centre of the cylinder and near enough to suit the grain to be threshed. The cylinder being governed by screws to raise or lower, and being suspended on roller boxes which are held down by springs an inclined board placed on the back part of the machine, the forward part of which comes close to the first bar of the concave to conduct the grain to come in under the cylinder. The other end of the cylinder extends out on one side of the machine, on which a wheel is made fast to apply the hand from above or wheel to put the machine on motion. The grain or corn passing between the surface of the Spur of the cylinder and the concave of bars.

What is claimed by this improvement is,

X5805

The spines acting upon the grain over the concave base.
